SCOTIA, CANADA.

CAR-ROOF.

1,155,807.

Specification of Letters Patent.

Patented Oct. 5, 1915.

Application filed July 6, 1914. Serial No. 849,249.

To all whom it may concern:

Be it known that we, SOREN HANSSON and ISAK MOELLER, residents of New Glasgow, in the Province of Nova Scotia and Dominion of Canada, have invented a new and useful Improvement in Car-Roofs, of which the following is a specification.

This invention relates to an improvement in car roofs, and particularly in roofs for 10 railway cars.

The object of the invention is to simplify and improve the general construction of car roofs, and provide a roof which can be readily manufactured at low cost, which is 15 to a certain degree flexible and therefore better able to withstand the racking strains of service, in which the number of parts is materially reduced, and which is so arranged as to materially reduce the leakage 20 of water, snow or the like to the inside of the car, and which also provides drainage gutters or channels for conducting to the outside of the car any water or moisture which may find its way through the joints 25 in the car roof.

The invention comprises the construction and arrangement of parts hereinafter described and claimed.

In the drawings Figure 1 represents a 30 partial plan view of a car roof embodying the invention, the left half showing the roof sheets removed; Fig. 2 is a longitudinal detail section, on a larger scale, taken on the line 2—2, Fig. 1; Fig. 3 is a detail plan view taken directly over one of the carlines, and at the side edge of the roof; Fig. 4 is a sectional elevation on the line 4—4, Fig. 3; Fig. 5 is a detail side elevation corresponding to Figs. 3 and 4; Fig. 6 is a plan view at one corner of the car; Fig. 7 is a section on the line 7—7, Fig. 6; and Fig. 8 is a cross section on the line 8—8, Fig. 1.

The roof frame comprises side plates 1, 45 which may be of any suitable section but are shown as Z-bars with their webs vertical and flanges horizontal, two or more longitudinal stringers or purlins 2, which are inverted channel members, as shown in Fig. 50 8, end plates 3, which are pressed plate metal members with their side and upper edges bent to form flanges, and transverse members or carlines 4. The end plates 3 have their flanges riveted to the side plates 55 1, and to the end roof sheets, as indicated at

and 6, and their webs to the corner post 7, which is also riveted to the web of the side plate. The edges of the end roof sheets are bent down over the end plates 3, as shown at 7^a, to insure a tight joint and prevent the entrance of rain or moisture. The longitudinal stringers are connected to the end plates by angle members and lie beneath and support the transverse carlines 4, which are riveted thereto, as indicated at 8. 60 The carlines are somewhat arched in the usual manner and at their ends rest upon and are riveted directly to the upper flanges of the side plates 1. The carlines may be of any suitable section, but preferably are 70 of some suitable section which provides a gutter or channel for carrying off any water, snow or moisture which may find its way through the joints between the roof sheets. In the form shown in the drawings, the carlines are of modified T section, being inverted with the webs 9 and edge flanges 10 75 extending upwardly and forming two channels or gutters 11 lying on opposite sides of the web. The web 9 is cut down on an 80 incline at each end of the carline, as indicated at 12, the end portion of the carline being also depressed downwardly where it rests on and is secured to the side plate 1.

The roof sheets, indicated at 13, are 85 formed of plate metal with the edges of adjacent sheets overlapping at the carlines. These roof sheets intermediate their edges lie flat upon the longitudinal stringers 2, but are not directly secured thereto. 90 At the sides of the car the edges of the roof sheets are bent downwardly over the side plates 1 and are riveted thereto, as indicated at 14. At the carlines the edges of the roof sheets are bent upwardly and rest 95 directly upon the edges of the upwardly extending flanges 10 of the carlines, the edge of one sheet being bent upwardly on an incline, preferably to a point beyond the upper edge of the flange 9 of the carline, as 100 indicated at 15, and the edge of the next roof sheet being bent upwardly and overlapping the edge of the other sheet and forming an inverted U, indicated at 16. This produces a water tight joint without the necessity of a special seam cap and to a large degree prevents water or moisture from passing through the joint between roof sheets. Also, the roof sheets are not riveted 105 to the longitudinal stringers or carlines and 110

consequently the roof has a certain amount of flexibility which enables it to withstand racking and warping strains. The inverted U formed by the bent edges of the sheets 5 is depressed or becomes shallower at the ends of the carlines, until at the extreme edges of the roof sheets which lap down over the side plates 1, the inverted U section is quite shallow and forms a restricted 10 channel, indicated at 17. This also produces a longitudinal extension 18 on each roof sheet at each end of the joint between adjacent roof sheets, which provides a material overlap between the roof sheets 15 where they are secured to the side plates, without the necessity of providing extra metal for this purpose. At the same time, the restriction of the channel 17 materially reduces the liability of snow or rain being 20 forced into the car along the eaves. Any water, moisture or snow which finds its way through the joint between roof sheets is trapped by the channels 11 and is conducted along the gutters formed thereby to 25 the sides of the car, where it is discharged over the side plates through the restricted channels 17, and runs down outside the car. The inverted U shaped edge portions of the roof sheets also form supports for 30 the running board saddles 20 which are bent metal members riveted directly to the edges of the roof sheets, as indicated at 21, and to which the usual running board 22 is secured. Preferably inner protecting plates 35 23 are placed underneath the inner heads of the rivet heads 21 to prevent water leaking through the riveted joint.

The construction described is very simple and can be readily manufactured. The 40 roof is also flexible so that damaging effects of warping strains are reduced, if not entirely eliminated. Also, the joints between roof sheets are simple, and form an efficient protection against the leakage of 45 water or moisture into the car, and the special form of carlines provides efficient gutters for carrying off any liquid which may find its way through the joint. At the same time, the restriction of the channels 50 for carrying off the water prevents snow or rain from beating its way into the car at the ends of the joint.

What we claim is:

1. A car roof, comprising side plates, car- 55 lines connecting the same and formed of inverted T sections each having a web and side flanges, and roof sheets secured to the side plates, the edges of adjacent roof sheets being bent upwardly over the webs of said 60 carlines into inverted U shape, the bent edge portions of said roof sheets being shallower at the ends of the joints between roof sheets to form restricted openings for the discharge

of water, each roof sheet at the end of a carline having a longitudinally extending 65 portion overlapping the next adjacent roof sheet and secured thereto.

2: A car roof, comprising side plates car- lines connecting the same and formed of inverted T sections having an upright web 70 and side flanges forming drainage gutters on opposite sides of said web, and roof sheets secured at their ends to the side plates and having their edge portions overlapping each other and also overlapping the webs of said 75 carlines but being free of connection thereto.

3. A car roof, comprising side plates, car- lines connecting the same and formed of inverted T sections having an upright web and side flanges forming drainage gutters on 80 opposite sides of said web, and roof sheets secured at their ends to the side plates and having their edge portions overlapping each other and also overlapping the webs of said carlines but being free of connection there- 85 to, said roof sheets also having portions adjacent their edges resting on the upper edges of the flanges of said carlines and supported thereby.

4. A car roof, comprising side plates, car- lines connecting the same and formed of inverted T sections having an upright web and side flanges forming drainage gutters on 90 opposite sides of said web, roof sheets se- cured at their ends to the side plates and 95 having their edge portions overlapping each other and also overlapping the webs of said carlines but being free of connection there- to, and longitudinal purlins located below said carlines and secured thereto, the roof 100 sheets resting on said purlins between ad- jacent carlines.

5. A car roof, comprising side plates, car- lines connecting the same and formed of inverted T sections having an upright web 105 and side flanges forming drainage gutters on opposite sides of said web, roof sheets se- cured at their ends to the side plates and having their edge portions overlapping each other and also overlapping the webs of said carlines but being free of connection there- 110 to, said roof sheets also having portions adjacent their edges resting on the upper edges of the flanges of said carlines and supported thereby, and longitudinal purlins located 115 below said carlines and secured thereto, the roof sheets resting on said purlins between adjacent carlines.

In testimony whereof, we have hereunto set our hands.
